UNITED STATES PATENT OFFICE.

JOHN A. L. WADDELL AND JOHN LYLE HARRINGTON, OF KANSAS CITY, MISSOURI.

LIFT-BRIDGE.

953,307.

Specification of Letters Patent. Patented Mar. 29, 1910.

Application filed June 26, 1908. Serial No. 440,463.

To all whom it may concern:

Be it known that we, JOHN A. L. WADDELL and JOHN LYLE HARRINGTON, both citizens of the United States, residing at 5 Kansas City, in the county of Jackson and State of Missouri, have invented certain new and useful Improvements in Lift-Bridges; and we do declare the following to be a full, clear, and exact description of the invention, 10 such as will enable others skilled in the art to which it appertains to make and use the same, reference being had to the accompanying drawings, and to the letters and figures of reference marked thereon, which form a 15 part of this specification.

Our invention relates to lift bridges and more particularly to a bridge having a single span that is adapted for carrying traffic over a ship canal, and for elevation to permit the passage of vessels there-beneath; the present invention being an improvement on the lift bridge disclosed in Letters Patent No. 506,571 issued to John A. L. Waddell, one of the present inventors, October 10th, 25 1893.

It is the object of the present invention to provide a lift bridge in which the movable span is raised and lowered from separate and disconnected towers; to provide a plurality of motors or drivers that may operate simultaneously or singly for actuating the lifting mechanism; to provide improved brake, stop, and lock mechanisms for automatically controlling the action of the movable span, and to provide improved tension regulating parts.

It is also our object to provide other improved details of structure which will presently be fully described and pointed out in the claims, reference being had to the accompanying drawings in which like reference numerals refer to like parts throughout the several views, and in which:—

Figure I is a view, in front elevation, of a 45 lift bridge constructed according to our invention. Fig. II is a top plan view of the same, the tower houses being horizontally sectioned to illustrate the inclosed transmission. Fig. III is an end view of one of the 50 towers, the tower house being vertically sectioned to illustrate the inclosed parts. Fig. IV is a slightly enlarged horizontal section on the line IV—IV, Fig. III. Fig. V is an 55 enlarged plan view of one of the transmission sets. Fig. VI is a side view of the same. Fig. VII is a detail view of the hand

winch and its connection with the driving shaft. Fig. VII is a detail view of the lifting span, illustrating the automatic locking mechanism. Fig. IX is an enlarged vertical section of the locking jaws and span pin, on the line IX—IX, Fig. X. Fig. X is an end view of the span locking parts. Fig. XI is an enlarged detail view of the equalizing weight supporting bracket. Fig. XII is a 60 similar view of the equalizer connecting the cables with the lifting span. Fig. XIII is a diagrammatic view of the direct and cross transmissions. Fig. XIV is a similar view showing a modified arrangement of the cross 65 transmission parts. Fig. XV is an enlarged detail view, in side elevation of the automatic brake parts. Fig. XVI is a circuit diagram.

Referring more in detail to the parts:— 75 1—1' designate the two bridge towers, which are supported on abutments 3 at opposite sides of the channel 2, and are wholly disconnected except for the transmission cables. As such towers and their supporting and 80 supported parts are substantially duplicates of each other, but one will be described in detail with the understanding that such description relates equally to both.

4 designates a lift span which extends 85 across the channel 2, and, when in its lowered position, is supported on the abutments 3 so that its flooring is on the road grade, in position for use as an ordinary bridge. The towers and lift span are preferably to be 90 constructed of structural steel.

At each end of the span are the offset arms 5 which extend outside the tower posts and are provided with laterally projecting guide channels 6 which are adapted to embrace 95 the guide flanges 7 that are rigidly mounted on the tower posts, to guide the span during its vertical travel; the fit of such parts being adapted to permit free vertical movement of the span although being sufficiently snug to prevent material longitudinal or lateral movement thereof. Revolubly mounted in bearings 10—10', that are supported on the top of tower 1, is a main shaft 11 which extends transversely to the tower and rigidly carries the gear wheels 12 and 13, the former of which engages the gear 14 on a motor shaft 15.

16 designates motors, arranged in pairs of any suitable type, one of which is located at each side of the tower and which are adapted for simultaneously actuating

the motor shaft 15 which is common to the pair of motors.

15' designates clutches, of an ordinary type, for throwing the motor shaft 15 into and out of operative connection with the motors.

Revolutely mounted in bearings 17-17' on tower 1 is a driven shaft 18 on which is rigidly mounted a gear wheel 18' that is adapted for constantly meshing with a gear 19 on an intermediate shaft 20 that is journaled in bearings 21 between the shafts 11 and 18. Rigidly mounted on the intermediate shaft 20 is a gear 22 which is adapted 15 for constant mesh with the gear 18 on the main shaft 11; the intermediate parts connecting the main shaft 11 with the driven shaft 18 being adapted for positively driving the latter at considerably slower speed than that at which the motor shaft revolves. Rigidly mounted on each end of the driven shaft 18 is a rear sheave 23 that is adapted 20 to partly project over the outer edge of the tower and is arranged preferably in alinement with a forward sheave 24 that is supported on bearings 25 and is adapted 25 to project over the inner edge of the tower.

26 designates cables, preferably four in number, which extend in pairs over the sheaves 23 and 24, and are attached at their respective ends to the span 4 and a counter balancing weight 27. To prevent an unequal strain being placed on any one of the cables in the event of their unequal contraction or expansion, or from other causes, we provide the span ends with an equalizer comprising the balance beams 28-29 which are pivotally connected by links 30 with opposite ends of a main beam 31, which is adapted to rock on a center pin 32 that projects therethrough and carries, at its ends, a yoke 33; said yoke being mounted at its lower end on a pin 34 in the end of the movable span. To each end of the small 45 balance beams 28-29 are pivoted the sockets 35 to which the span ends of the cables 26 are attached.

At the weight ends, the cables are attached to sockets 36 which are pivoted to the rockings beams 37 which in turn are pivotally connected with the ends of the main beam 38 by links 39; the main beam being balanced at its center on a pin 40 which supports a yoke 41; the parts just described being substantially identical with the equalizing parts at the span end. Supported on yoke 41 is a rod 42 that extends through a weight 27 that is preferably constructed of concrete and formed in a single piece of sufficient weight to balance one half of the weight of the lift span. At each end of the weight 27 is an eye pin 44, which is connected with the balance pin 40 by links 45, for the purpose of steadyng the weight during its upward and downward travel.

As illustrated in the drawings, the weight carrying parts are duplicated on the opposite sides of each tower so that each half of the span is counterbalanced by a single weight which is connected with the span by 70 duplicate sets of cables.

With the bridge equipped with a double set of motor and transmission parts, of the character described, and with the lift span balanced at each end by the weights 27, it 75 would be possible to raise and lower the span by simultaneously operating both pair of motors; the friction of the paired cables 26 on their sheaves being sufficient to overcome the friction and the inertia of the parts. It 80 is one of the objects of our invention, however, so to combine the parts that, should one pair of motors become inoperative, the transmitting mechanism may be operated and the span raised or lowered by the pair of 85 motors on either tower. To accomplish this we have provided the following mechanism:

On the shaft 11 on each tower are rigidly mounted the rear sheaves 46 or 46'. On the 90 side of the tower at one side of the channel are the bearings 47-48 arranged in substantial alinement with the rear sheaves 46 on the shafts 11 and in which are axially mounted the forward sheaves 49-50. On 95 the opposite side of the other tower are forward sheaves 49'-50', which correspond in structure and arrangement with the forward sheaves 49-50 on the opposite tower, the only difference being that the bearings and 100 forward sheaves are on opposite sides of opposite towers.

51 designates an endless cable that is adapted for travel on the sheaves 46, 49 and 50 on the tower 1 and over the sheave 46' on 105 the tower 1'. Between the forward sheaves 49-50, cable 51 carries a tension sheave 52 from which a weight 53 is hung for the purpose of constantly tensioning the cable 51 so that any slack due to contraction or expansion, or other causes, may be taken up and a close contact of the cable with its sheaves secured.

54 designates a cable that is adapted for travel over the sheaves 46', 49', 50' and 46 115 and is provided with a tension sheave 52' and weight 53' which are of the same construction and operated in the same manner as the parts on the opposite sides of the towers, that have just been described.

It will be noted that the cables 51-54 are crossed in extending between the towers so that the weight 53 tensions the cable 51 between the top of the rear sheave 46 and the bottom of the rear sheave 46' while the weight 53' tensions the cable 54 between the bottom of the rear sheave 46 and the top of the rear sheave 46', so that the cable 51 acts directly between the top of the rear sheave 46 and bottom of the rear sheave 46' when 120 125 130

the paired motors are operated in one direction and the cable 54 acts directly between the bottom of the rear sheave 46 and top of the rear sheave 46', when the motors are operated in the opposite direction. In this way the power from the transmission on one tower may be instantly applied to the transmission on the opposite tower to secure simultaneous action on both ends of the span, a result which could not be obtained should both cables have their weights suspended between either the top or bottom of the respective sheaves, for the reason that while the transmission on one tower is operating in one direction, the cables would pull directly on the opposite transmission, but should the motion be reversed the pull would first come on the weight 53 or 53', and raise same slightly before reaching the opposite tower, thereby causing the end of the span adjacent to the tower on which the operating motor is located to start on its upward or downward travel before the opposite end is actuated, and produce an uneven operation of the span, which might result in the span jamming between the towers. When the ends of the span are unequally loaded the transmission mechanism further acts to compel synchronous action of the two drivers by placing the greater portion of the whole load upon the motors which tend to run at the greater speed and relieving the slower motors of part of their load, thus tending to reduce the speed of the faster motors and increasing the speed of the slower ones. It can also be seen that by continuing to revolve the rear sheaves 23 after the span has reached the limit of its travel in either direction, the tension on the paired ropes 26 will be equalized.

In Fig. XIV we show a modified arrangement of the cables 51 and 54 and their sheaves, in which the idlers are all arranged in the same tower; such arrangement being operative but not as desirable as the one previously described.

Referring now to Figs. IX and X on the abutment 3 beneath each end of the span 4 is a brake frame 54 having a pin 55. Loosely mounted on the pin 55 are the locking levers 56 which are arranged in pairs and are provided with hook ends 57 which are adapted to project over the pin 58 on the under side of the span from opposite sides, for holding the span firmly in position; each lever being provided with a weight arm 59 that is adapted to normally retain the levers in locking position, but which may be rocked by the downward engagement of the span pin to enable such pin to pass between the locking jaws to reach its locking position.

In Fig. VIII, 60 designates a cable having branches that are extended over pulleys 61, the latter being so located that when

the cable is drawn in one direction the locking levers may be rocked away from the span pin to free the latter when it is desired to raise the span. 62 designates a solenoid which is connected with a switch 63 so that it may be energized at will from a point to which the lead wires may run, and has a core 64 which is connected with the cable 60, so that when the solenoid is energized the core will be retracted and the cable actuated to rock the locking levers and free the span pin.

While we have provided means for operating the structure from the motor on one tower only should that on the other become inoperative, we wish also to provide means for operating by hand should the motors on both towers become useless. This is done by providing the shaft 11 with a beveled gear 65, with which a pinion 66 on a vertical shaft 67 is adapted to mesh; shaft 67 having at its lower end a pinion 68 that is adapted to mesh with a pinion 69 on a forwardly projecting shaft 70; said shaft 70 having a clutch 71 with which a mating clutch 72 on a shaft 73 is adapted to connect for the purpose of actuating the shaft 11 and its connected parts from the shaft 73. On the end of shaft 73 is a beveled gear 74 which meshes with a like member 75 on a shaft 76; the latter being extended upwardly to a desired height and provided with a hand winch 77.

While the operating motors may be controlled entirely by hand and suitable bumpers provided for lessening the impact of the span as it approaches the upward or downward limit of its travel, we prefer to provide means for automatically shutting off the motors, and applying brakes to the transmission as the span reaches either its upper or lower position; the following mechanism being preferred:

78 designates a band wheel that is mounted on each of the motor shafts 15.

79 designates brake frame arms that are pivotally mounted at their lower ends in a frame 80 and are provided with shoes 81 that are adapted to swing into engagement with the periphery of the band wheel 78; 115 82 designating a spring that connects the opposite frame arms and is adapted for yieldingly pressing the shoes against said wheel.

83 designates a lever arm on each of the 120 brake frames which is connected with an actuating member 84, preferably a solenoid, so that such actuating member may retain the brake levers out of contact with the brake band wheel when the motors are in 125 operation, but will release said member to the action of their spring when the motors are shut off.

85 designates a controller adapted for starting and stopping the motors and for 130

opening or closing a circuit through the solenoids, and which, being of any ordinary type, is not shown in detail; such controller being used when motors of an electrical type are employed and an equivalent mechanical device substituted therefor when necessary.

To each set of cables 26 is rigidly attached a clamp 86 which is adapted to rock the levers 87, which are pivotally mounted on the top and bottom of the towers 1 and 1' as the span approaches the upward or downward limit of its travel, such levers being so connected with the motor and brake controller that when rocked by the cable clamps 21 they will actuate the controller to effect an automatic shut down and application of the brakes. Inasmuch as such automatic parts may in themselves be of any well known structure, a detailed illustration and description thereof is not given, as the only invention claimed for these parts is their combination with a bridge of the present type.

Under ordinary conditions the span 4 will remain in its lowered position so that it may be used as an ordinary bridge, the floor of the span being level with the road grade and the span ends locked by the end levers 56. When it is desired to raise the span, the locking levers are rocked to release the span pins 58 so that they may pass from between the locking jaws. The lock being open, the motors on each of the bridge towers are started in operation, causing a revolution of shafts 18 and sheaves 23 through the transmission 19 previously described. The lift span and weights being supported by the cables 26, and being evenly balanced thereon, the weight of the parts is supported on the sheaves 23 and 24 so that there is a decided friction of the cables against the sheave peripheries that will cause a travel of the former upon a revolution of the latter; the weights descending and the span ascending until the latter has reached the upward limit 45 of its travel. As the span approaches its upper position, the clamp on the cable 26 rocks the lever 87 on the tower, which actuates the controller, and through it shuts off the motors and applies the brakes in the manner described, so that the span may assume its upper position without a damaging impact against the tower parts or straining of the mechanism. When it is desired to lower the span, the motors are thrown into 55 operation through the controller and operated in a direction opposite to that just described; the travel of the cables 26 being thereby reversed so that the span is lowered and the weights lifted in the same manner 60 as for an upward travel of the span. As the span has been moved above the locking levers, at the first movement, the locking levers automatically rock back to their operative position, so that as the span approaches its 65 normal position the pin 58 strikes against the

beveled edges of the locking levers and forces same apart against the tension of their weighted arms, to enable the pins to assume their locked position beneath the hook ends when the levers are rocked back by their own weight to enable such hooks to engage and hold the span pins and prevent an accidental displacement; the motors being cut off and the brakes applied in the same manner as described in reference to the upward 75 travel.

While the span may be operated in the manner described, a more perfect operation is secured by providing the cross cables 51-54, which unite the transmission on opposite towers; the weights 53-53' providing the necessary tension for developing friction on the sheaves for operating the parts. With a connection of this class, should one of the motors become inoperative, it may be cut out by the clutch 16 and the opposite motor will drive its own transmission and through the cable 51 or 54 transmit power for actuating the opposite shaft 11 for the purpose of simultaneously raising or lowering both ends 90 of the span and weights. Should both motors become inoperative, the clutch 16 may be operated to throw the motor shaft out of connection with the transmission, the hand winch connected with the drive shaft 11 and the transmission operated through the winch. While we have shown a plurality of motors for operating each of the shafts 11, it is readily apparent that a single motor may be provided for the purpose, if desired.

Having thus described our invention, what we claim as new therein and desire to secure by Letters Patent is:—

1. A lift bridge comprising towers, motor mechanism mounted upon the top of each tower, each mechanism comprising a motor-shaft, a motor coupled to the motor shaft, an intermediate lift span, gearing geared with the motor shaft, and flexible connections between the ends of the lift span and the gearing.

2. A lift bridge comprising towers, motor mechanism mounted upon the top of each tower, each mechanism comprising a motor, an intermediate lift span, and means whereby said span may be actuated by the simultaneous action of the motors or by the independent action of each motor.

3. A lift bridge comprising towers, motor mechanism mounted upon the top of each tower, each said mechanism comprising a shaft, a pair of motors clutched to said shaft; and an intermediate lift span adapted for movement by the simultaneous action of the paired motors on opposite towers or by the independent action of either pair of motors alone.

4. A lift bridge comprising towers, an intermediate lift span, a motor-driven shaft upon the top of each tower, a sheave rigidly

mounted on each shaft, idler sheaves, and a cable passing over both driving shaft sheaves and the idler sheaves, substantially as and for the purpose set forth.

5. A lift bridge comprising disconnected towers, an intermediate counterbalanced span supported from said towers, a motor-driven shaft on the top of each tower having power transmitting parts adapted for 10 frictional contact with the span-supporting means, a sheave wheel on each driven shaft, a pair of idler sheaves for one end of each set of power mechanisms, and a cable connecting relative sheaves on the opposite 15 driven shafts and adapted for travel over one set of idler sheaves, each of said cables having a weight suspended by a pulley between its pair of idler sheaves, substantially as and for the purpose set forth.
20. 6. A lift bridge comprising towers, a pair of motors mounted upon the top of each tower, a lift span adapted for actuation by said paired motors, and means for equalizing the work of the paired motors on the two 25 towers to secure an even travel of the span.
7. A lift bridge comprising towers, a pair of motors mounted upon the top of each of the towers, of the motors of each pair being coupled, transmission means connecting the paired motors on opposite towers, and 30 equalizing devices comprised in said transmission means.

8. In combination, a lift bridge tower, a

motor driven shaft thereon, a pinion on said shaft, a countershaft, a gear thereon, driven 35 by said pinion, sheaves 46, 46' on said countershaft, a pinion 13 on the countershaft, a shaft 21, a gear on said shaft, driven by said pinion 13, a pinion 19 on said shaft 21, a second bridge tower, sheaves thereon, and 40 two endless cables passing over the sheaves 46, 46' and over the sheaves on the second bridge tower.

9. In combination, a lift bridge tower, a motor driven shaft thereon, a pinion on 45 said shaft, a countershaft, a gear thereon, driven by said pinion, sheaves 46, 46' on said countershaft, a pinion 13 on the countershaft, a shaft 21, a gear on said shaft, driven by said pinion 13, a pinion 19 on said shaft 50 21, a shaft 18, a gear thereon driven by said pinion 19, sheaves 23 on shaft 18, sheaves 24 on the tower, a lift span between the towers, cables 26 connected to said span and passing over sheaves 23 and 24, counterweights on 55 cables 26, a second bridge tower, sheaves thereon, and two endless cables passing over the sheaves 46, 46' and over the sheaves on the second bridge tower.

In testimony whereof we affix our signatures in presence of two witnesses.

JOHN A. L. WADDELL.
